UNITED STATES PATENT OFFICE.

EDWARD S. COBB, OF WHITTIER, CALIFORNIA, ASSIGNOR TO COBB SHOCKLESS CROSSING CORPORATION, OF NEW YORK, N. Y., A CORPORATION OF NEW YORK.

RAIL-SUPPORT.

1,252,663.

Specification of Letters Patent. Patented Jan. 8, 1918.

Original application filed January 11, 1917, Serial No. 141,739. Divided and this application filed March 6, 1917. Serial No. 152,521.

To all whom it may concern:

Be it known that I, EDWARD S. COBB, a citizen of the United States, residing at Whittier, in the county of Los Angeles, 5 State of California, have invented new and useful Improvements in Rail-Supports, of which the following is a specification.

This invention relates to means for supporting rails, especially for supporting movable rails, and more particularly for supporting such movable rails as I describe in Patent No. 1,074,082, issued September 23, 1913, and in my application for switch and frog, S. N. 141,739 filed January 11, 1917, 15 and co-pending herewith.

It is a particular object of this invention to provide an efficient, simple and strong support for a movable rail, which shall support the rail with the necessary safety and 20 security and at the same time give the desirable elasticity. Specifically, it is an object of this invention to provide a rail support that will give the necessary rigid base for such a movable rail as I describe, and 25 will also give the same resilient action of support to the movable rail as is given to rails where they are supported in the ordinary manner upon wooden ties or the like; for the purpose of making the movable rails, 30 such as I describe, absolutely uniform with the main rails of a track, and to thus make the passage of trains over an intersection, crossing, or switch as smooth and shockless 35 as possible. I have described in said Letters Patent, and in said co-pending application, forms of intersections and of switches in which vertically movable rail portions are utilized, and in which the vertically movable rail portions form smooth and unbroken 40 continuations of the main stationary rails leading up to the intersection or switch. Such constructions as therein described provide an unbroken rail surface for the passage of wheels; and the present invention 45 provides a support for the movable rail portions of such a nature as to make the movable rail portions perfect continuations of the main stationary rails.

In the following specification I describe 50 my invention as applied to a switch structure; not because my invention is limited to such a switch structure, but for the reason that a description of its application to such a structure most fully sets forth my inven-

tion and also indicates how the present invention may be applied to intersections, 55 crossings, or the like.

Accordingly, I illustrate said preferred application of my invention to a switch structure in the accompanying drawings, in 60 which Figure 1 is a plan of my switch structure with the present invention applied; Fig. 2 is a longitudinal vertical section taken as indicated by line 2—2 on Fig. 1; Fig. 3 is an enlarged cross section taken as indicated by line 3—3 on Fig. 1; Fig. 4 is an 65 enlarged cross section taken as indicated by line 4—4 on Fig. 1; and Fig. 5 is an enlarged cross section taken as indicated by line 5—5 on Fig. 1; 70

In the drawings the numerals 10 and 11 designate the main rails of a track and the numerals 10^a, 11^a and 10^b 11^b, designate the main stationary rails of switch tracks (either of which may form a direct continuation 75 of the main track 10—11, and one of which may, of course, be in reality the main track itself). Vertically movable switch rails 10^c and 11^c extend between the switch points P and the frog F. By alternately 80 raising and lowering these rails 10^c and 11^c, either of the switch tracks may be made to be a direct continuation of the main track 10, 11. For instance, by raising the switch rail 11^c and lowering the switch rails 10^c 85 the rails 11 and 11^a are directly connected for passage of flanged wheels, while the switch rail 10^c is lowered sufficiently to allow flanged wheels to pass directly over the rails 10—10^a. The details of construction 90 and operation of the switch mechanism herein shown are completely described in my said co-pending application; and it is not necessary herein to go further into said details, except to show that my rail support may be and is applied to such a structure to support the movable rail portions 95 thereof. Whether the movable rail portions form continuations across a switch, or across an intersection or crossing, is immaterial to 100 the present invention. Also, as will be seen, it is immaterial whether the movable rail portions, as 10^c and 11^c, be straight or curved. In the particular instance herein shown, I have illustrated them as being curved in 105 order to show the specific details of support of a curved rail.

Under each of the movable rails I place a

supporting beam structure 20. Each beam structure is made up of a metal beam, preferably of rolled steel of such form of cross-section as will be best adapted to any particular case. For the present case I am showing a channel beam, as illustrated at 21; and in or on this steel beam I place a resilient, preferably wooden, filler block 22, whose upper surface is preferably slightly above the upper edges of flanges of the beam 21. The upper surface of this wooden filler block forms the direct supporting surface for the rails 10° and 11°. Now, this wooden filler block, and the beam 21, are, in each instance, of sufficient width and length to lie under all parts of the supported rail, as is clearly shown in Fig. 1. In other words, where the rail is curved, the beam may be of considerably greater width than the base 20 of the rail, so as to take in and support all portions of the rail base. Of course, where the rail is of lesser curvature, or straight, it is not necessary that the beam be so wide as in a case where the rail is of greater 25 curvature. The supporting beam is, in all cases, preferably straight, so that it may be supported upon suitable supports arranged in a straight line. This straight line support of the rail and of the beam obviates any tendency of the rail and beam to twist 30 over laterally due to its supports being out of line; and, at the same time, the fact that the beam underlies all parts of the rail makes it possible to put each support for 35 the beam directly under the rail itself. This will be seen to be true by inspection of the various views, in connection with the following description. In the specific form illustrated, I show three supports for each 40 beam. These supports are preferably in the form of cams 25 mounted upon cam shafts 26 and rotating under cam bearings 27 which are secured under the beams 21. These cam bearings 27 may be secured to 45 the beams in any desired manner; but I may prefer to secure them by the same bolts 28 that are used to hold the rails 10° and 11° down on the filler blocks 22. These bolts 28 which hold the rails down pass directly 50 through the rail bases and through filler blocks 22, and are secured below the beams 21; and it is a function of these bolts to hold the rails down, to prevent their upward movement away from the supporting beam, 55 and at the same time to allow the slight downward resilient motion of the rails due to the pressure and weight imposed upon them. That is, although the rails are held down firmly upon the beams, and upon the 60 filler blocks, they are only supported by the resilient filler blocks and are not in any way directly supported by the steel beams. The steel beams form the main and effective support for the rails, and they 65 give the requisite rigidity and solidity; yet

the rails are solely directly supported by the resilient wooden filler blocks which give the required resilience of action and support to make the movable rail portions act exactly as the ordinary rails act when supported 70 upon wooden sleepers or upon sleepers of like resiliency.

In the form of device shown herein, the different cam shafts 26 are connected together by chain drives 30 so that all of the cams 75 may be operated simultaneously, to raise and lower the supporting beams and the supported rails. The cams for each beam are all set so that they reach their highest and lowest points simultaneously, so that 80 each beam is operated in horizontal position. And it will be particularly noted that the cams are placed so as to extend completely across under the beams, and the cam bearings 27 are placed so as to not only be under 85 the whole width, or practically the whole width, of the beams, but also to be under the supported rails. In other words, each beam is supported as a straight line beam, upon supports arranged in a straight line; 90 but these supports are of sufficient width to underlie all portions of the supported rail; so that, where the rail is curved, it is supported at all points upon a structure which has no tendencies to tip over laterally. 95

I have described the specific details of a preferred form of my invention not because my invention is necessarily limited thereto, but in order to make plain the particular application of my invention to a 100 specific situation, as well as to set forth the general features of my invention. I accordingly state that the devices herein described may be varied and modified, as will occur to those skilled in this art, without departing from my invention, except as indicated by the following claims.

Having described a preferred form of my invention, I claim:

1. In combination with a rail, a support 110 therefor embodying a supporting beam beneath the rail and arranged longitudinally thereof, a resilient filler block continuously supported on said beam directly supporting the rail, and means for supporting the beam 115 at points spaced along its length.

2. In combination with a rail, a support 120 therefor embodying a supporting beam beneath the rail and arranged longitudinally thereof, a resilient filler block continuously supported on said beam directly supporting the rail, means securing the rail by holding it down to the beam and filler, the sole direct support of the rail being through the resilient filler block, and means for supporting 125 the beam at points spaced along its length.

3. In combination with a rail, combined raising and supporting means therefor, embodying a supporting beam arranged longi- 130

- tudinally beneath the rail, a resilient filler block on said beam and directly forming the sole support of the rail, and cam means below said beam to support it and raise and lower it. 5
4. In combination with a rail, combined raising and supporting means therefor, embodying a steel supporting beam arranged longitudinally beneath the rail, a resilient wooden filler block on said beam and directly forming the sole support of the rail, means securing the rail by holding it down to the beam and filler, and cam means below said beam to support it and raise and lower it. 10
5. In combination with a curved rail, combined raising and supporting means therefor, embodying a straight steel supporting beam arranged longitudinally beneath the rail, the beam being of such width as to lie under all parts of the curved rail, a resilient wooden filler block on said beam forming the sole direct support of the rail, said filler block extending under all parts of the rail, and forming the sole direct support of the rail, means securing the rail by holding it down to the beam and filler, and cam means below said beam to support it and raise and lower it. 15
- 20 6. In combination with a curved rail, a supporting means therefor embodying a straight steel beam arranged longitudinally beneath the rail and of such width as to lie under all parts of the curved rail, and a resilient filler block on said beam forming the sole direct support of the rail, said filler block 25 extending under all parts of the curved rail, and means for securing the rail by holding it down on the resilient filler block without supporting the rail. 30
7. In combination with a curved rail, a supporting means therefor embodying a straight steel beam arranged longitudinally beneath the rail and of such width as to lie under all parts of the curved rail, a resilient filler block on said beam forming the sole direct support of the rail, said filler block 35 extending under all parts of the curved rail, and means for securing the rail by holding it down on the resilient filler block without supporting the rail. 40
8. In combination with a rail, combined raising and supporting means therefor, embodying a supporting beam arranged longitudinally beneath the rail, a resilient filler block continuously supported on said beam and directly forming the sole support of 45 said rail, and means spaced along the length of said beam to support it and raise and lower it. 50

In witness that I claim the foregoing I have hereunto subscribed my name this 22nd day of January, 1917.

EDWARD S. COBB.
